DRILLING BUCKET

Benjamin E. Bertran, Los Angeles, Calif., assignor
of one-half to Josie A. Bertran

Application November 7, 1930. Serial No. 494,040

8 Claims. (Cl. 255—67)

My present invention relates to drilling means, and particularly to drilling buckets for drilling holes in the ground for constructing building foundations, or for the drilling of wells or other holes.

The objects of this invention are: first, to provide a drilling bucket for the purpose mentioned whereby the contents of the bucket, after the same is placed therein from a drilling operation, 10 may be easily and quickly emptied even though the contents is of a sticky or adhesive nature, such as clay, which is ordinarily very difficult to remove from drilling buckets of this character; second, to provide a drilling bucket of this class 15 which may be made very small for drilling small holes, and from which, even though small, the dirt, or other drilled material, may be easily removed; third, to provide a device of this class which may be opened at the whole of one side 20 of the lower end of the bucket for removing the contents thereof, and which is yet very strong and cannot be readily distorted when the opening is closed by the gate or door provided therefor; fourth, to provide a digging bucket of this class 25 in which is provided an inverted cone shaped drilling head at the lower end and which is also divided so that half a cone is carried by the main body portion of the bucket and also by the gate so as to provide for rigidity of construction of the 30 lower ends of both the main bucket member and of the gate, and also to facilitate the removal of the contents from the bucket; fifth, to provide a novel arrangement of cutting members and clearance openings in a bucket of this class; sixth, 35 to provide novel and simple latch means for holding the gate in a closed position and also novel and simple means for actuating the latch; seventh, to provide simple and novel means for raising, lowering and rotating the bucket; and, eighth, to provide a drilling bucket of this class 40 which is very simple and economical of construction, efficient, and which will not readily deteriorate or get out of order.

With these and other objects in view, as will appear hereinafter, I have devised a new drilling bucket having certain novel features of construction, combination and arrangement of parts and portions, as will be hereinafter described in detail and particularly set forth in the appended 45 claims, reference being had to the accompanying drawing and to the characters of reference thereon which form a part of this application in which:

Figure 1 is a side elevational view of my drilling bucket in its preferred form of construction show-

ing the same open at its lower end and the gate shifted to one side; Fig. 2 is a top view thereof; Fig. 3 is a fragmentary sectional elevational view thereof taken through 3—3 of Fig. 1; and, Fig. 4 is a sectional view thereof taken through 4—4 of Fig. 1 as the drilling bucket appears when the same is closed and ready for the drilling operation.

Like characters of reference refer to similar parts and portions throughout the views of the drawing.

The drilling bucket, illustrated in the drawing, is similar in appearance to other drilling devices of this class in that it is cylindrical in shape and provided at its lower end with an inverted conical cutting head with cutting members in said head. In this instance, however, the bucket is made essentially of two members, namely, a main bucket member or shell 1, and a gate or door 2. The member 1 is cylindrical in shape and is cut away at one side of the lower portion, as indicated by 1a. This cut away portion is in the form of a semi-cylindrical opening which, when the device is in operation, is enclosed by a correspondingly shaped semi-cylindrical gate 2. This opening and gate extend preferably the greater distance of the length of the bucket leaving a substantially narrow band 1b at the upper end. The gate 2 is hinged, by hinges 3, at one longitudinal edge to a corresponding longitudinal edge of the cut away portion of the bucket member 1, as shown in Figs. 2 and 4. The other or opposite edge 2a abuts against the opposite longitudinal edge 1c when the gate is closed.

The gate is held in a closed position by a latch 90 which consists of a rod 4 reciprocally mounted within and longitudinally with respect to the axis of the bucket, and preferably close to the inner wall thereof. This rod is provided at its lower end with an offset portion 4a and intermediate its ends with another latch portion 4b spaced from the shank of the latch and positioned in vertical alignment with the offset latch portion 4a. These latch portions are reciprocally mounted and guided in lugs 5 secured to the inner wall of the bucket member 1 adjacent the edge opposite the hinges. The gate 2 is also provided with lugs 6 which are secured to the inner side of the gate adjacent the free longitudinal edge, as shown in Figs. 3 and 4. These lugs 6 are adapted, when the gate is closed, to be positioned below the lugs 5, and are provided with holes or eyes 6a which are adapted to align with the latch portions and to receive the latter when the gate is intended to be held in a closed 100 105 110 position.

position. At the upper end of the bucket member 1 is secured a bail 7 which is in the form of an inverted U-shaped member with the downwardly extending legs thereof secured to the inside wall of the band portion 1b of the bucket member. On this bail is pivotally mounted a latch operating lever 8 which consists of a supporting and bearing portion 8a from one end of which extends a handle 8b and from the opposite end of which extends an arm 8c. The end of the arm 8c is connected to the upper end of the shank of the latch 4 by means of a link 9. Thus when the latch operating lever is shifted to the solid line position shown in Fig. 1, the crank arm 8c raises the latch and disconnects the free edge of the gate from the bucket member 1. When the handle 8b is shifted inwardly to the dotted line position, as shown in Fig. 1, the crank arm 8c is directed downwardly and forces the latch portions below the lugs 5 and into the holes 6a of the lugs 6, when the gate is closed.

The lower or apron portion of the bucket member 1 and the gate 2 are of substantially the same shape, and each is provided at its lower end with a conical portion or bottom member 10 and 11, respectively, each conical portion being approximately a half cone with the vertex directed downwardly. At one of the inclined edges of each of the semi-cone shaped bottom or head members 10 and 11 is secured a cutting member 12 which is deflected downwardly at a slight angle. These cutting members, when the gate is closed, form cutting means at substantially diametrically opposite sides of the cone shaped head from the vertex toward the circumference. The opposite inclined edge of each of the semi-cone shaped portions is offset inwardly, as indicated by 10a and 11a. These offset portions form long slots or openings opposite, respectively, the cutting members on the gate and the apron portion of the bucket member 1, and permit the material cut during the drilling operation to be directed into the bucket.

Below the upper portion of the bail 7 may be provided a cross member 13 which may be suitably reinforced with respect to the upper portion of the bail. Through the central portions of the upper portion of the bail 7 and the bar 13 is extended a stem 14, commonly known as a "Kelly bar". This stem is prevented from being shifted longitudinally with respect to the bucket and bail by pins or bolts 15 extending through the stem below the bar 13 and above the upper portion of the bail. The stem is also preferably of square cross section and extends through correspondingly shaped openings in the bar 13 and the bail 7. Thus the stem or "Kelly bar" 14 is adapted for raising and lowering the bucket and for rotating the same during the drilling operation.

It will be here noted that the gate 2 is so hinged to the bucket member 1 that even though the latch is accidentally raised and the free edge of the gate disconnected from the bucket member 1, the gate will nevertheless remain in a closed position until the bucket, filled with earth, is raised above the hole which is being drilled.

Though I have shown and described a particular construction, combination and arrangement of parts and portions, I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

1. In a drilling means of the class described, a cylindrical bucket having an inverted conical drilling head at its lower end, said bucket having a substantially semi-cylindrical gate at the lower portion for opening one side of the lower portion of the bucket, said gate carrying substantially one-half of the inverted conical drilling head and the other half being carried by the lower end of the main portion of the bucket, and cutting means at one inclined edge of each of said conical drilling head portions, the cutting means being arranged at substantially diametrically opposite sides of the head, the opposite edges of said drilling head portions being spaced inwardly and upwardly respectively from the cutting means to facilitate the entering of the material cut into the shell. 95

2. In a drilling means of the class described, a cylindrical shell having a substantially semi-cylindrical cut away portion at one side of its lower end, a semi-cylindrical gate pivoted on the shell adapted, when closed over the opening of the shell, to form a cylindrical receptacle therewith, and adapted to be opened about its pivoted portion for removing the contents thereof, and inverted semi-cone shaped bottom members on the lower ends of the shell and gate forming with each other a substantially conical cutting head, each of the bottom members being provided at one inclined edge with cutting means spaced inwardly and upwardly from the opposed inclined edge of the other member. 110

3. In a drilling means of the class described, a bucket comprising a pair of shell members hinged to each other and adapted to be opened with respect to each other, each shell member having a separate rigid bottom member rigidly secured thereto at its lower end, said bottom members forming with each other, when the shell members are closed with respect to each other, a head for the lower end of the bucket, and a cutting member secured to each of the bottom members at one edge thereof the other or remaining edge portions being pressed inwardly and upwardly to form with said cutting members horizontally directed openings into said bucket. 120

4. In a drilling bucket, a cylindrical bucket having an inverted conical drilling head integrally connected thereto at its lower end, said bucket having a substantially semi-cylindrical gate at its lower portion for opening one side of the lower portion of the bucket, said gate having substantially one-half of the inverted conical drilling head integrally secured thereto and the other half integrally secured to the lower end of the main portion of the bucket and cutting means along one margin of each of said portions of the inverted conical head the other margins being spaced upwardly and inwardly from said cutting members and forming therewith substantially horizontally and arcuately extending passages communicating with the interior of said bucket. 135

5. A drilling bucket comprising, a pair of semi-cylindrical shell members, hinge and latch means joining said shell members, the one of said shell members projecting above the other and forming a continuing cylindrical or band portion, a rigid bail joined to said band portion, semi-conical drilling heads joined to the bottoms of said shell members, cutting members along one edge of said drilling head, the remaining edges of the drill- 150

ing heads axially overlapping the cutting members and spaced upwardly and inwardly therefrom forming baffle passages permitting the forcing of earth into said shell members but hindering gravity flow of the earth therefrom.

6. A drilling bucket comprising, a pair of semi-cylindrical shell members, hinge and latch means joining said shell members, the one of said shell members projecting above the other and forming a continuing cylindrical or band portion, a rigid bail joined to said band portion, semi-conical drilling heads joined to the bottoms of said shell members in angular relation therewith, each of said drilling heads having a radially and upwardly directed straight edge, a cutting member secured thereto, the remaining edges of the drilling heads axially overlapping the cutting members and spaced upwardly and inwardly therefrom forming baffle passages permitting the forcing of earth into said shell members but hindering gravity flow of the earth therefrom.

7. A drilling bucket comprising, a pair of semi-cylindrical shell members, hinge and latch means

joining said shell members, drilling heads joined at the bottoms of said shell members, cutting members along one edge of each drilling head, the remaining edges of the drilling heads axially overlapping the cutting members and spaced upwardly and inwardly therefrom forming baffle passages permitting the forcing of earth into said shell members but hindering gravity flow of the earth therefrom.

8. A drilling bucket comprising, a pair of semi-cylindrical shell members, hinge and latch means joining said shell members, semi-conical drilling heads joining the bottoms of said shell members in angular relation therewith, each of said drilling heads having a radially and upwardly directed straight edge, the remaining edges of the drilling heads axially overlapping the cutting members and spaced upwardly and inwardly therefrom forming baffle passages permitting the forcing of earth into said shell members but hindering gravity flow of the earth therefrom.
